(57) **CLAIM**

We claim the ornamental design for a radio extender, as shown and described.

DESCRIPTION

FIG. 1 is an isometric view, from the top front left, of a radio extender.

FIG. 2 is an isometric view, from the bottom front right, of the radio extender.

FIG. 3 is an isometric view, from the bottom back right, of the radio extender.

FIG. 4 is an elevation view from the left of the radio extender.

FIG. 5 is an elevation view from the right of the radio extender.

FIG. 6 is a plan view from the top side of the radio extender

FIG. 7 is a plan view from the bottom side of the radio extender.

FIG. 8 is an elevation view from the front of the radio extender; and,

FIG. 9 is an elevation view from the back of the radio extender.
